UNITED STATES PATENT OFFICE.

WALTER S. BALES, OF DES MOINES, IOWA, ASSIGNOR OF ONE-FOURTH TO EARL M. SINCLAIR, OF DES MOINES, IOWA.

DITCHING AND EARTH-MOVING MACHINE.

1,316,074.

Specification of Letters Patent. Patented Sept. 16, 1919.

Application filed March 3, 1915. Serial No. 11,924.

To all whom it may concern:

Be it known that I, WALTER S. BALES, citizen of the United States of America, and resident of Des Moines, Polk county, Iowa, have invented a new and useful Ditching and Earth-Moving Machine, of which the following is a specification.

The object of this invention is to provide an improved construction for a ditching and 10 earth-moving machine especially adapted for railway use.

A further object of this invention is to provide improved means for mounting the main frame of such a machine for rotary 15 adjustment on a support such as a truck.

A further object of this invention is to provide a main frame mounted for rotary adjustment on a turntable and for rectilinear reciprocation on and relative to said 20 turntable.

A further object of this invention is to provide an improved digger frame and means for mounting the same.

A further object of this invention is to 25 provide improved means for pivotally connecting a digger frame to a main frame whereby said digger frame may be carried in vertical position for operation and in horizontal position on said main frame when 30 not in operation, for storage or transportation.

A further object of this invention is to provide improved means for pivotally mounting a digger frame on a vertical axis.

A further object of this invention is to 35 provide an improved construction for securing adjustment of a digger frame vertically.

A further object of this invention is to provide improved means for mounting a 40 prime mover relative to a digger frame.

A further object of this invention is to provide an improved construction for endless diggers.

My invention consists in the construction, 45 arrangement and combination of elements hereinafter set forth, pointed out in my claims and illustrated by the accompanying drawing, in which—

Figure 1 is a front elevation illustrating 50 my improved machine mounted on a railway car and in position for operation. Fig. 2 is a side elevation illustrating the machine in folded or inoperative position. Fig. 3 is a side elevation, partly in section and on an

enlarged scale, of the digger frame and end- 55 less diggers. Fig. 4 is a plan and Fig. 5 a side elevation, on an enlarged scale, illustrating the horizontal conveyers and means for driving the same simultaneously. Fig. 6 is a vertical section on the line 6—6 of Fig. 4, 60 Fig. 7 is a connecting chute being removed. Fig. 7 is a side elevation of one end of a horizontal conveyer.

In the construction of the machine as shown the numeral 10 designates generally a 65 truck such as a railway car adapted for travel on track rails 11, 12 and to be propelled by any suitable motive power (not shown). A main frame is constructed of suitable material such as channel or angle 70 bars, and is designated generally by the numeral 13. Skids 14, 15 are mounted loosely and slidingly and arranged longitudinally on the truck 10, are spaced apart laterally and carry a platform 16. A large gear 17 75 is mounted for rotation on the platform 16 and has a table 18 fixed to its upper face. Slide bearings 19, 20 are mounted on, fixed to and rise from the table 18 and slidingly embrace, hold and support the lower members of the frame 13. The large gear 17 is in mesh with and adapted to be rotated by a small gear 21 fixed to a stub shaft 22 mounted for rotation in a vertical position in the platform 16 and a bearing bracket 23 carried thereby. The stub shaft 22 projects at 80 its upper end above the bearing bracket 23 and is formed angular in cross-section for the reception of a crank of common form (not shown) by which said shaft may be rotated for the rotation of the gears 21 and 17, the table 18 and the frame 13 and elements carried thereby. A stub shaft 24 is mounted for rotation in the upper part of one of the slide bearings 19 and a pinion 25 is 85 mounted on and fixed to said shaft. The pinion 25 is in mesh with a rack 26 mounted on and fixed to one of the lower horizontal members of the frame 13. The stub shaft 24 projects beyond the bearing 19 at one end 90 and is formed angular in cross-section for the reception of a crank handle of common form (not shown) by means of which said shaft may be rotated to the end of rotating the pinion 25 and reciprocating the rack 26, 95 frame 13 and elements carried thereby.

A prime mover of any desired type, here illustrated as a steam hoisting engine of

common form designated generally by the numeral 27, and provided with hoisting drums 28, 29, is mounted on the rear portion of the main frame 13. A roof or canopy 30 preferably is mounted over the prime mover 27 and is supported from the frame 13 by standards 31.

In the construction of the digging mechanism a digger head 32 is employed, which 10 head is preferably of substantially trapezoidal form in side elevation. A mast 33 is fixed to and depends from the lower side of the digger head 32, and said mast preferably is formed in two telescoping sections adapted 15 to be adjusted vertically and held in adjusted position by a set screw 34. The upper portion of the telescoping mast 33 is pivotally mounted in a bearing frame 35, and is restrained against downward movement 20 therein by a set collar 36 fixed to said mast and resting on the top of said frame. Arms 37 are fixed to and extend rearwardly from the bearing frame 35 and are pivoted at their rear ends on a rod 38 mounted transversely of the forward end portion of the frame 13. The arms 37 are limited as to 25 downward movement by a stop frame member 39 mounted transversely of the forward end of the frame 13 in front of the pivot rod 38, by means of which said arms are sustained in horizontal position when the machine is in operation. Bearings 40 are mounted on and rise from the bearing frame 35 and a worm shaft 41 is mounted for rotation 30 in said bearings, and engages and is adapted to drive a face wheel 42 fixed to the upper end of the mast 33 and digger head 32. The worm shaft 41 is connected at its rear end by a universal joint 43 to a shaft 44 mounted for rotation in bearings 45 on the main frame 13 and formed with a crank handle 46 on its rear end. By this means the digger head and elements carried thereby may be rotated to set the digging 45 devices at the desired angle, relative to the main frame.

The digger head 32 is forked at its upper corners and shafts 47, 48 are mounted for rotation therein and sprocket wheels 49, 50 are mounted in spaced pairs on said shafts. The mast 33 is forked at its lower end and a shaft 51 is mounted for rotation therein, and spaced sprocket wheels 52 are mounted on and fixed to said shaft. Endless chains 53, 54 are mounted on and connect the respective members of the pairs of sprocket wheels 47, 48 and 51 and are adapted for travel thereon. Any suitable excavating and elevating buckets, such as 59, here shown conventionally, may be carried in spaced relation by the endless chains 53, 54. A prime mover 60, here illustrated as a twin cylinder steam engine, is mounted on a platform 61 carried by the digger head 32, and may be supplied with steam by a pipe 62 leading from the

boiler of the prime mover 27 and supported by hangers 63 from the roof 30.

Sprocket wheels 64, 65 are mounted on and fixed to the engine shaft 66 of the prime mover 60 and are connected by sprocket chains 67, 68 to sprocket wheels 69, 70 mounted respectively on the shafts 47, 48. By this means the chains 53, 54 are driven for rotation of the buckets. It is to be understood that either set of sprocket gearing 64—67—69 or 65—68—70 may be employed independently if desired to drive the endless diggers.

A grooved quadrant 71 is mounted on and fixed to the arms 37 carrying the digger frame, adjacent the pivot 38. A cable 72 is fixed to the arm 37 at the base of the quadrant 71, runs through the groove of said quadrant and passes rearwardly and is fixed to and adapted to be wound on the drum 29. By this means a pulling force may be applied to the arms 37 to raise them to vertical position on the main frame 13, to the end of folding the digger frame and elements carried thereby to horizontal position on the forward portion of said main frame, as illustrated in Fig. 2, when the machine is not in operation. The steam pipe 62 is provided with a flexible section 62^a to permit movement of the digger head as above described.

A horizontal conveyer 73 is mounted on the forward portion of the main frame 13 and has its forward end embraced and supported by a yoke 74 slidably mounted on the frame member 39. The rear end portion of the conveyer 73 is supported by a yoke 75 resting on a transverse member of the frame 13 and pivotally connected thereto by a spindle 76. A second horizontal conveyer 77 is mounted on the frame 13 at the rear of the conveyer 73 and on a lower plane, the forward end of the conveyer 77 lying beneath and communicating with the rear end of the conveyer 73. The forward end of the conveyer 77 is pivotally connected by a spindle 78 to a transverse member of the frame 13. The rear end of the conveyer 77 is supported by a yoke 79 slidably mounted on a transverse member of the frame 13. A bevel gear 80 is fixed to the rear shaft 73^a of the conveyer 73 and is in mesh with and adapted to be driven by a bevel gear 81 mounted for rotation on the spindle 76. A spur gear 82 is fixed to and for rotation with the bevel gear 81 on the spindle 76, and said spur gear is in mesh with and adapted to be driven by a pinion 83 fixed to the upper end of a vertical shaft 84. The shaft 84 is mounted for rotation in bearing brackets 85 carried by the members of the frame 13 supporting the spindles 76, 78. A pinion 86 is fixed to the lower end of the shaft 84 and is in mesh with and adapted to be driven by a spur gear 87 mounted for rotation on the

spindle 78. The pinion 86 is fixed to the lower end of the shaft 84 and is in mesh with and adapted to be driven by a spur gear 87 mounted for rotation on the

spindle 78. A bevel gear 88 is fixed to the upper face of the spur gear 87 and is in mesh with and adapted to drive a bevel gear 89 fixed to the forward shaft 77^a of the horizontal conveyer 77. A grooved pulley 90 is fixed to the lower face of the spur gear 87 and a cable 91 passes around said pulley and is adapted to be driven by the prime mover 27 to the end of driving simultaneously the two horizontal conveyers 73, 77.

A chute 92 is mounted in and leads rearwardly from the digger head 32 and is designed to receive earth from the endless digger when the buckets thereof arrive in horizontal and inverted position, and to discharge the same to the forward end of the conveyer 73. A chute 93 is mounted at the rear end of the conveyer 73 and is designed to connect said conveyer with the conveyer 77 and to transfer earth from the former to the latter conveyer.

In practical use the machine is employed for excavating, cleaning, enlarging or deepening ditches at the sides of railway right of ways. The gear 17 and table 18 are rotated in the manner above described to position the frame 13 at an angle to the truck 10, and the cable 72 is slackened to the end of permitting the excavating frame 30 to assume, through gravity, its vertical position at the side of the truck as shown in Fig. 1. The pinion 25 is rotated as above described to reciprocate the rack 26, and the frame 13 and excavating frame, to position said excavating frame as desired laterally relative to the truck 10 and the track on which it stands. The engine 60 is operated to drive the chains 53, 54, and the buckets 59 thereon take up the earth and deliver the same to the chute 92 and conveyer 77, whence it is passed to the conveyer 77 by the chute 93. The conveyer 73 may be manually adjusted through an arc at its forward end, by sliding yoke 74 on frame member 39, to bring it beneath the chute 92, depending upon the position of the excavator frame. The conveyer 77, which may be adjusted through an arc at its rear end, by sliding the yoke 79 on the frame 13, delivers the earth to the desired place on the truck 10. The excavator frame may be rotated on a vertical axis, by means of the worm shaft 41 and crank 46, to the end of causing the endless diggers to cut at the desired angle 55 relative to the path of advance of the machine. For ordinary cuts or cleaning work it is desirable to position the excavator frame in a plane parallel to the rails 11, 12. When it is desired to trim the banks of a cut, the elevator frame is positioned at an angle intersecting the path of advance ahead of the machine and cuts at an angle to the bank. The depth of the cut may be regulated and adjusted by adjusting the telescoping mast 33 through the set screw 34, the length of

the chains 53, 54 being adjusted by removing or inserting sections containing the excavating devices.

The location of the prime mover 60 on the excavator head is of peculiar advantage in securing a direct and positive drive without the use of cumbersome and troublesome gearing.

It will be understood that the machine may be used for excavating ahead of the truck 10 by setting the excavator frame alternately on opposite sides of the track, at angles to the path of advance.

I claim as my invention—

1. A machine of the class described, comprising, in combination, a main frame, bell-crank levers pivoted to said main frame each formed with arms at right angles to each other and each arm adapted to rest at times in horizontal position on the frame, and an excavator frame carried by the foremost arms of the bell-crank levers and substantially at right angles thereto and adapted to be carried in vertical position when said arms are resting on the main frame and in horizontal position above the main frame when the rearmost arms of the bell-crank levers are resting on the main frame.

2. A machine of the class described, comprising, in combination, a main frame, bell-crank levers pivoted to said main frame each formed with arms at right angles to each other and each arm adapted to rest at times in horizontal position on the frame, an excavator frame carried by the foremost arms of the bell-crank levers and substantially at right angles thereto and adapted to be carried in vertical position when said arms are resting on the main frame and in horizontal position above the main frame when the rearmost arms of the bell-crank levers are resting on the main frame, a grooved quadrant fixed to and connecting the arms of one of said bellcrank levers, a cable secured to the foremost arm of such lever and passing over said quadrant, and means for applying draft to said cable to oscillate said lever.

3. In a machine of the class described, a carrier frame suitably supported, a mast pivoted on a vertical axis in said carrier frame, a sprocket wheel carried by the lower end of said mast, a head of substantially trapezoidal form carried by said mast above said carrier frame, sprocket wheels carried by opposite ends of said head, and endless digging devices mounted on said sprocket wheels.

4. In a machine of the class described, a carrier frame suitably supported, a mast pivoted through said frame and adapted for oscillation on a vertical axis, a head of substantially trapezoidal form carried by the upper end of said mast, a gear wheel carried by the upper end of said mast, a worm

gear carried by said carrier frame and meshing with said gear wheel, sprocket wheels from, sprocket wheels carried by the lower portions of said mast and on end of said mast and by opposite ends of said head, and endless digging devices 15 mounted on said sprocket wheels.

5. In a machine of the class described, a carrier frame suitably supported, a mast mounted through said carrier frame and pivoted for rotary oscillation on a vertical axis, said mast being adjustable as to length, a head carried by the upper end of said mast, and endless digging devices 10 mounted on said sprocket wheels.
